UNITED STATES PATENT OFFICE.

VIRGIL W. BLANCHARD, OF NEW YORK, N. Y.

TYPE-WRITING MACHINE.

SPECIFICATION forming part of Letters Patent No. 321,479, dated July 7, 1885.

Application filed April 1, 1884. (No model.)

To all whom it may concern:

Be it known that I, VIRGIL W. BLANCHARD, a citizen of the United States, residing at New York city, in the county of New York and State of New York, have invented certain new and useful Improvements in Type-Writers, of which the following is a specification, reference being had therein to the accompanying drawings, in which—

10 Figure 1 is a perspective view of a type-writer finger-key constructed in accordance with my invention. Fig. 2 is a side view of the same with its lower portion in section. Fig. 3 is an enlarged view in section of the 15 socket to receive the lower end of the finger-key stem. Fig. 4 is a perspective view of the lower end of said key-stem.

My invention relates to improvements in type-writing machines in which a series of 20 pivoted type-levers are operated by means of finger-keys in connection with key-levers and connecting-rods.

In the accompanying drawings, A represents a type-writer key-lever, generally made of a 25 strip of wood, around which is secured a strap, a, of sheet metal, bent in the middle of its length so as to form two ears, a', extending above the top edge of the key-lever. This strap is secured to the latter in the usual manner by means of a tongue, a'', cut and punched 30 in from the metal of one of the ears a' and pressed into close contact with the upper edge of the key-lever. To the ears of said strap is pivoted, by means of the rivet c, a link having its lower end, b, rectangular or flattened and 35 its upper end, b', cylindrical. This upper end is first bored centrally or provided with a hole, b'', having a diameter equal to or slightly smaller than the diameter of the stem d of the 40 finger-key. The upper end, b', is then slotted vertically with a saw to form a mortise, b''', extending under the bottom of the hole b'', and the latter portion of the mortise forms side

bearings for the flattened faces of the tenon d', formed on the lower end of the finger-key stem, 45 to rest against and prevent the rotation of said stem.

By the above-described means a shoulder is formed within the bottom of the hole b'' within the link corresponding with the shoulder at 50 the lower end of the cylindrical portion of the stem d, and also a slightly-springy bearing is formed above the shoulder within the same link that strongly clasps the stem at that point, and a rectangular bearing is produced 55 also below the shoulder to hold the stem at that point.

The upper end of the stem d is provided with a finger-key, D, of the usual form and construction. 60

Having now fully described my invention, I claim—

1. A type-writer key-lever having pivoted to the strap a thereof a link, the lower end of which is flattened and its upper end bored 65 centrally, as at b'', and slotted to form a mortise extended under the perforation b'', in combination with the cylindrical stem d, having a rectangular tenon, d', at its lower end, a finger-key, D, at its upper end, substantially as 70 and for the purpose described.

2. The combination of the finger-key D, provided with a cylindrical stem and a tenon at the lower end of the latter, and a link provided with a cylindrical socket, and a slot extending across and under said socket, with a key-lever and a strap pivoted to said socketed link, substantially as and for the purpose described. 75

In testimony whereof I affix my signature 80 in presence of two witnesses.

VIRGIL W. BLANCHARD.
